HEATING UNIT

Hartwig N. Baruch, White Marsh, Otis T. Amory,
Newport News, and Obed A. Bloxom, Battery
Park, Va.

Application February 28, 1935, Serial No. 8,770

3 Claims. (Cl. 126—132)

This invention relates to heating units, and is an improvement over the embodiment disclosed in our copending applications Serial No. 681,628 filed July 21, 1933, Patent No. 2,046,051, and Serial No. 728,998 filed June 4, 1934, Patent No. 2,048,675 for improvements in heating units particularly adapted for insertion in open fireplaces.

An object of this invention is the provision of a heating unit capable of being mounted in the present construction of open fireplaces for the purpose of heating water to be distributed to heat exchange devices disposed within a dwelling or the like and comprising a hot water heating system and wherein the products of combustion are adapted to pass through flues in the upper portion of the unit so as to increase the heat exchange capacity of the unit.

Another object of this invention is to provide a heating unit of this character which may be constructed of relatively thin flexible sheet metal forming inner and outer jackets suitably spaced apart in a uniform manner and maintained in spaced apart relation notwithstanding the expansion of the walls thereof under temperature changes, the unit including a replaceable grate and grate front structure.

A further object of this invention is to provide a heating unit capable of utilizing as much of the heat generated by the heating means as possible and which is so constructed that the draft may be readily controlled at selected portions of the firebox or grate.

With the foregoing and other objects in view, the invention will be more fully described herein-after, and will be more particularly pointed out in the claims appended hereto.

In the drawings, wherein like symbols refer to like or corresponding parts throughout the several views,

Figure 1 is a vertical sectional view of a heating unit constructed according to an embodiment of this invention, the view being taken on the line 1—1 of Figure 2.

Figure 2 is a front elevation partly broken away and in section of a heating unit of this character mounted in an open fireplace construction.

Figure 3 is a front elevation of the unit provided with doors.

Figure 4 is a side elevation of the structure shown in Fig. 3.

Figure 5 is a vertical sectional view of a modified form of heating unit.

Referring now to the drawings, and first to Figures 1 and 2, the numeral 10 designates generally an outer jacket, and the numeral 11 designates

nates generally an inner jacket disposed in spaced relation to the outer jacket.

The outer jacket 10 comprises a bottom plate or wall 13 which is secured along its front edge to a front outer wall 12, and is secured along its rear edge to a rear wall 14. This rear wall 14 at a point spaced upwardly from the bottom thereof is inclined forwardly as at 15 so as to provide a constricted upper end or throat for the heating unit. The front wall 12 is substantially vertical and is adapted to engage snugly against the inner side of the front wall 16 of the fireplace structure. A top wall 18 is secured at its rear edge to the upper edge of the upper portion 15 of the rear wall 14, and is secured at its front edge to the upper edge of the front wall 12.

A pair of outer side walls 19 have their marginal portions secured to the bottom, front, rear and top walls of the outer jacket in a well-known manner, and these walls 19 are adapted to snugly fit against the side walls of a fireplace. Each of the side walls 19 is provided adjacent the bottom thereof with intake nipples 20, and with outlet nipples 21 adjacent the upper ends thereof so that the unit may be readily coupled with a hot water heating system.

The inner jacket 11 comprises a bottom plate or wall 22 which is secured at its front edge to the front plate or wall 12 at the bottom of the opening 23 in the front of the unit, and is secured at its rear edge to a rear wall 24. The rear wall 24 is shaped similar to the outer rear wall 14, being provided with a forwardly inclined upper portion 25. The rear wall members 14 and 24 are held in uniformly spaced apart relation by means of spacers or tie members 26 welded or otherwise secured to the walls 14 and 24. An upper inner wall 27 is secured to the upper end of the rear wall 24, and the junction between these walls 24 and 27 is preferably formed by a curved portion 28. A front inner wall 29 is secured to the front edge of the upper or top wall 21 of the inner jacket, and is connected to the front outer wall 12 by a connecting plate 30 which defines the upper edge of the opening 23.

Rearwardly convergent side wall members 31 have their marginal portions secured to the bottom, rear, top and front walls, and these inner side wall members 31 are disposed in spaced parallel relation to the outer side wall members 19, being held in spaced relation by spacing or tie members 26.

As will be noted from the drawings, and particularly Fig. 1, the inner bottom wall 22 is in-

clined in an upward and rearward direction, with the intake nipple 20 discharging into the space between the two jackets 10 and 11 adjacent the front of the bottom wall 22. The space between the rear edge of the bottom wall 22 and the outer bottom wall 13 is substantially greater than the distance between the outer and inner rear walls 14 and 24, respectively. By spacing the inner bottom wall 22 at its rear portion in this manner the water within the hollow bottom of the unit will flow more freely in a rearward and upward direction.

The products of combustion are permitted to pass upwardly through the unit by means of ducts in the form of pipes or tubes 32 which are connected at their lower ends to the inner top wall 27 and at their top or upper ends to the outer top wall 18. The water in the upper portion of the unit is adapted to engage about the periphery of the tubes 32 and to be additionally heated thereby before the water flows out through the outlets 21.

Grate supporting brackets 33 of substantially L-shape are secured to the inner rear wall 24 above the inner bottom 22, and side brackets 33a are secured to the inner side walls 31. A grate structure generally designated as 34 is adapted to be disposed on the brackets 33 and 33a and comprises a grate frame 35 of open construction within which a plurality of grate bars 36 are mounted. The bars 36 are substantially V-shaped in transverse section, and a grate bar operating member 37 extends below the bars 36 in substantially the center thereof, being mounted adjacent its rear end in a depending lug 38, and at its front portion in a depending lug 39. The sliding movement of the operating member 37 is limited by a stop member 40 secured to the member 37 inwardly of the front lug 39.

Each grate bar 36 has a depending bifurcated lug or member 41 loosely engaging about the operating member 37, and the lugs 41 are disposed between spaced apart collars 42 secured to the member 37 one on each side of each lug 41.

A basket member 43 is secured at its lower end to the grate frame 35, and extends entirely across the opening 23. The member 43 forms the front wall of the grate 34, and is preferably perforate so as to permit the entrance of air to the fuel disposed on the grate.

A sliding door or draft controlling member 44 has an overturned upper edge portion slidingly engaging the upper edge portion of the member 43. Preferably this member 44 is of a length substantially equal to one-half of the width of the opening 23 so that when fresh fuel is placed in the grate 34 the draft controlling member 44 may be moved to the side of the grate opposite from the fresh fuel so that the partially burned fuel will not burn as freely as the fresh fuel. This draft controlling member is preferably imperforate in its upper portion 45, and the lower portion 46 extends below the grate 34 and is provided with a plurality of draft openings 47. A slide 48 is carried by the lower portion 46 and controls the opening and closing of the draft openings 47.

The inner side walls 31 of the inner jacket 11 are each provided with aligned brackets 49 for supporting a horizontally disposed bar (not shown) and upon which suitable utensils may be hung as is customary in open fireplaces.

Water for domestic use may be heated by means of a heating unit secured to and extending above the hereinbefore described heating

unit. This domestic water heating unit comprises inner and outer jackets 50 and 51 respectively which are suitably spaced apart and formed substantially to the configuration of the throat of the fireplace. The front portion of this heating unit extends rearwardly and upwardly, as shown in Figure 1, and the unit is provided with an inlet 52 adjacent the bottom thereof, and with an outlet 53 adjacent the top thereof and to which pipes may be connected.

A damper 54 is secured to the domestic water heating unit, and is operated by a bar 55 extending through the front wall 16 of the fireplace which is connected to the damper 54 by means of a connecting link 56.

Referring now to Figures 3 and 4, there is here disclosed a heating unit similar in every detail to the heating unit disclosed in Figures 1 and 2. In this construction the outer jacket 19a has secured to the front wall 12a a pair of doors 57 provided with transparent windows 58. These doors 57 have the front wall thereof outwardly or forwardly offset, and dampers 59 may be provided in these doors.

Ash doors 60 provided with slides 61 are disposed below the upper doors 57 and are hinged to the wall 12a in any well known manner.

In Figure 5 there is disclosed a further form of heating unit comprising an outer jacket 10b and an inner jacket 11b similar to the jackets 10 and 11, and in which the bottom wall 22b is inclined similar to the wall 22. In this form, however, the flues or pipes 32b extend below the top wall 27b of the inner jacket 11b, and are connected to a baffle plate 62 which has a forwardly and upwardly extending rear portion 63. This baffle 62 prevents the pocketing of air in the rear upper portion of the unit.

It will be noted from Fig. 1 that a self-contained unit is there shown in which the main portion thereof is composed of spaced walls forming the bottom portion, the rear portion, and the side portions. The rear portion, and the side portions have their walls diverging from each other at the uppermost part of this portion of the unit so as to form an enlarged chamber, the upper and lower walls of which are parallel with each other. A plurality of flue pipes, positioned adjacent each other, pass through this enlarged chamber, and the spaces between the flue pipes are closed by the upper and lower walls. Naturally, the uppermost portion and the lowermost portion of the flue pipes are open to permit the products of combustion to pass therethrough. Superimposed upon this main portion of the unit is another heating unit also composed of spaced walls acting as a water jacket, and this has peripherally disposed walls which rise directly upon the top of the main portion of the unit, and one of the walls, preferably the front wall, of this upper member is inclined rearwardly towards the rear wall so as to form a constricted opening. This constricted opening is regulated by means of a damper. By reason thereof, the products of combustion, exhausting from the upper part of the flues, have their heat extracted by the spaced walls, and, in consequence, as much heat as possible is extracted from the products of combustion, first by the spaced walls of the main heater itself, then by the enlarged chamber at the upper part of the heater, and finally by the heater portion above the flues.

This self-contained unit is adapted to be placed into the open part of a fireplace and all that is necessary is to connect suitable pipes for the wa- 75

ter supply and for the passage of the heated wa-
ter.

It is obvious that various changes and modifi-
cations may be made in the details of construc-
tion and design of the above specifically described
embodiment of this invention without departing
from the spirit thereof, such changes and modifi-
cations being restricted only by the scope of the
following claims.

10 What is claimed is:—

1. In a fireplace heating means including a hol-
low walled hot water heater insertable in a fire-
place opening; a second hollow walled domestic
water heater open at the top and bottom and
15 mounted on the top of the first named heater, said
second heater having front, side, and rear walls
and having in its upper part a constricted open-
ing, and a damper plate carried by said second
heater to regulate the size of the constricted open-
20 ing.

2. The combination with a jacketed heating
unit insertable in a fireplace opening, of a do-
mestic water heater comprising spaced front,
side and rear walls the front wall of which is

inclined toward the rear wall to form a construct-
ed opening, said heater resting on the top of the
heating unit, a damper for regulating the size
of the constricted opening and connecting means
connecting said damper with said heater.

3. A heating unit insertable in a fireplace com-
prising hollow communicating side, rear and bot-
tom walls constructed of sheets of material and
having an open front, a hollow top formed by the
side and rear walls diverging from each other and
10 forming also a front wall, a plurality of flues ex-
tending through said hollow top and having their
upper and lower faces open and the spaces be-
tween the flues closed by the walls forming the
hollow top, jacketed walls extending peripherally
15 around the hollow top and extending above said
hollow top and above the flues, one of said walls
being inclined from the front to the rear of the
unit forming a constricted opening and a damper
for regulating said opening.
